UNITED STATES PATENT OFFICE.

WILLIAM A. WILKINSON, OF MINNEAPOLIS, MINNESOTA.

DESIGN FOR A BASE FOR BAND-SAW MILLS.

SPECIFICATION forming part of Design No. 24,351, dated May 28, 1895.

Application filed January 26, 1893. Serial No. 461,539. Term of patent 14 years.

To all whom it may concern:

Be it known that I, WILLIAM A. WILKINSON, a citizen of the United States of America, residing at Minneapolis, in the county of Hennepin and State of Minnesota, have invented and produced a new and original Design for a Base for Band-Saw Mills, of which the following is a specification, reference being had to the accompanying drawings, forming a part thereof, and in which—

Figure 1 is a perspective view showing the front end and side of a band-saw-mill base embodying my design. Fig. 2 is a similar perspective view showing the rear end and opposite side of the base.

Both views are deemed necessary to fully illustrate my design.

The leading features of my design are as follows: First, the lower part of the base hav-

ing the forward extension 2, the arch portion 3, the bracket portions 4, the feet 5, between which and the lower edges of the part 3 are slots 6; and, second, the rear part of the base extending downward in curves and terminating in the approximately flat portion 7, which has the foot ledge 8 and the brackets 9. The lower part of the base also has an upper ledge 10.

Having thus described my design, what I claim is—

The design for a band saw mill base, substantially as shown and described.

In testimony whereof I have hereunto set my hand this 30th day of December, A. D. 1892.

WILLIAM A. WILKINSON.

In presence of—

C. G. HAWLEY,
F. S. LYON.
